UNITED STATES PATENT OFFICE.

ROBERT S. RILEY, OF WORCESTER, MASSACHUSETTS, ASSIGNOR TO SANFORD RILEY STOKER COMPANY, OF WORCESTER, MASSACHUSETTS, A CORPORATION OF MASSACHUSETTS.

ASH SUPPORT FOR MECHANICAL STOKERS.

Application filed January 29, 1924. Serial No. 689,359.

To all whom it may concern:

Be it known that I, ROBERT S. RILEY, a citizen of the United States, residing at Worcester, in the county of Worcester and 5 State of Massachusetts, have invented a new and useful Ash Support for Mechanical Stokers, of which the following is a specification.

This invention relates to a mechanical 10 stoker and particularly to improved devices for supporting and agitating the ash and refuse at the rear of the stoker and for preventing the formation of clinkers upon the rear or bridge wall of the stoker. The 15 invention is shown as applied to a commercial underfeed stoker of the type shown in applicant's prior Patent No. 1,322,822, issued November 25, 1919.

The general object of my invention is to 20 provide an ash supporting grate beyond the refuse dumping devices in a mechanical stoker, together with suitable mechanism for giving such a grate repeated raising and lowering movements.

25 My invention also comprises novel supporting and air supplying means for such a grate. By thus supporting and agitating the ash and refuse adjacent the bridge wall and by supplying air under pressure thereto, I am able to more completely consume the 30 combustible material in the refuse and to largely prevent the formation of clinkers on the bridge wall.

35 Further features of my invention relate to combinations of parts which will be hereinafter described and more particularly pointed out in the appended claims.

A preferred form of the invention is 40 shown in the drawings, in which

Fig. 1 is a sectional side elevation of my 45 improved ash support, together with certain associated parts of an underfeed stoker;

Fig. 2 is a fragmentary front elevation of 50 the ash support and its operating means;

Fig. 3 is a fragmentary sectional elevation taken along the line 3-3 in Fig. 1;

Fig. 4 is a side elevation of one form of 55 operating mechanism for moving my improved ash support; and

Fig. 5 is a detail plan view of a portion 60 of the operating mechanism.

Referring to the drawings, I have indicated a dumping plate 10 mounted at the rear of a stoker retort, a portion of the retort

side wall being indicated at 11. The plate 55 10 is held in operative position by a roll 12 mounted on a rack bar 13 which may be moved forward in the stoker to lower the plate 10 when the refuse is to be dumped. These parts may be constructed and operated 60 exactly as shown in my prior Patent No. 1,322,822, to which reference is made for a more complete description.

The usual bridge wall is indicated at 15 and is shown as supported upon a pair of 65 I-beams 16 spaced apart to form an air chamber 17. A series of heavy castings 18 are secured to the I-beams and support the front portion of the bridge wall 15, as clearly shown in Fig. 1. The lower portions of 70 the castings 18 are provided with segmental guideways 19 (Fig. 3) and with suitable air openings 20 between each pair of guideways.

Ash supporting grates 21 are provided 75 with depending arcuate supports 22, the upper concave edges of which fit between the guideways 19, the lower convex portions of which are provided with rack teeth 23. The supports 22 are of hollow construction and not only uphold the grates 21 but also provide connecting air passages 22^a between the outlets 20 of the air chamber 17 and the grates 21. An opening 22^b in the concave upper face of each support 22 registers with an opening 20 in the air chamber 17 when 85 the parts are in normal operative position but is closed off when the grates 21 are lowered to dumping position.

Operating pinions 24 are mounted on a 90 shaft 25 and engage the rack teeth 23 upon 90 the different grate supports 22. The tooth spaces of the pinions 24 are indicated as cut away or bevelled (see Fig. 2) to prevent the accumulation of dirt or ashes therein. It may also be noted that the pinions 24 are 95 provided with flanges 44 extending as far as the outer faces of the pinion teeth and engaging bearing surfaces 45 (Fig. 3) on the supports 22, so that the weight and pressure of the supports 22 and the grates 21, 100 together with the refuse supported thereby, is borne largely by the flanges 44 and only to a small extent by the teeth of the pinions 24.

The grates 21 are of hollow box-like construction and their upper faces are provided with indirect or zig-zag air passages through 105 which air will be conveyed to the refuse

supported thereon, while the direct entrance of refuse to the air passages 22^a is retarded.

Any suitable and convenient mechanism may be provided for oscillating the shaft 25, one such form of mechanism being shown in Figs. 4 and 5. An arm 30 is loosely mounted on the shaft 25 and is connected by a link 31 to a bell crank 32 mounted upon a fixed pivot 33. The bell crank 32 is connected by a link 34 to a head 35 having a bearing 36 for a crank pin 37. The crank pin 37 is regularly rotated and may be mounted on the end of the crank shaft which drives the coal feeding rams, shown in my prior Patent No. 1,322,822.

As the crank pin is rotated, motion is transmitted through the link 34, the bell crank 32 and link 31 to oscillate the arm 30 about the shaft 25. A hand wheel 40 is loosely mounted on the end of the shaft 25 and the adjacent faces of the hand wheel 40 and the arm 30 are provided with clutch teeth adapted for engagement by a sliding clutch collar 41 keyed on the shaft 25. When the collar is moved to the right into operative position in Fig. 5 the refuse supporting grates 21 will be regularly oscillated or given limited up and down movement by the automatic mechanism shown in Fig. 4. When the clutch collar is moved to the left, the refuse supporting grates 21 may be moved to any desired position manually.

It will be understood that the automatic movement of the grates is of limited extent, so that the refuse supported thereby is agitated but is not permitted to escape past the grates 21 or the plates 10 to the ash pit. When the refuse is to be dumped, the grates 21 may be swung downward manually to the extreme position indicated in dotted lines in Fig. 1, or the refuse may be dumped by moving the rack bars 13 forward and allowing the dumping plates 10 to swing downward. If desired, a combination of these two movements may be used.

The provision of an air admitting refuse supporting grate not only assists in consuming the last remnants of combustible material in the refuse but also, by continually agitating the refuse adjacent the bridge wall, these grates practically prevent the formation of clinkers upon the bridge wall, a most desirable result.

Having thus described my invention and the advantages thereof, I do not wish to be limited to the details herein disclosed otherwise than as set forth in the claims, but what I claim is:

1. In a stoker, a movably mounted refuse-supporting grate, means to give said grate repeated limited raising and lowering movements to agitate the refuse while said grate remains in operative ash-supporting position, means to give said grate an additional lowering movement away from ash-supporting position to discharge refuse therefrom, and means to supply air under pressure to said grate during its limited movements and so long as it remains in ash-supporting position and to cut off the air supply during its additional lowering movement and so long as said grate is in lowered position. 60 65

2. In a stoker, a movably mounted refuse supporting grate, automatic means to give said grate repeated limited raising and lowering movements to agitate the refuse while said grate remains in operative ash-supporting position, manual means to give said grate an additional lowering movement away from ash-supporting position to discharge refuse therefrom, and means to supply air under pressure to said grate during its limited movements and so long as it remains in ash-supporting position and to cut off the air supply during its additional lowering movement and so long as said grate is in lowered position. 70 75 80

3. In a stoker, a refuse dumping device, a refuse supporting grate positioned beyond said dumping device and mounted for oscillating movement, automatic means to oscillate said grate while in ash-supporting position, means to dump said grate, and means to supply air under pressure to said grate in every operative ash-supporting position thereof, and during said oscillating movements, the supply of air being interrupted when the grate is lowered to dumping position. 90 95

4. In a stoker, a bridge wall, a casting fixed in said bridge wall and having arcuate guide-ways formed therein, a refuse-supporting grate having a depending arcuate supporting portion fitting said guide-ways, said supporting portion being movable 100 therein to carry said grate to and from ash-supporting position, and means to supply air under pressure to said grate in every operative ash-supporting position thereof, said grate being movable downward and 105 rearward beneath said bridge wall for dumping the refuse. 110

In testimony whereof I have hereunto affixed my signature:

ROBERT S. RILEY.
